assignor to The French Renovating Company,
Cleveland, Ohio, a corporation of Ohio

Application March 2, 1936, Serial No. 61,436

Term of patent 14 years

To all whom it may concern:

Be it known that I, Albert B. Beitman, a citizen of the United States, residing at Cleveland Heights, in the county of Cuyahoga and State of Ohio, have invented a new, original, and ornamental Design for a Scrubbing Machine, of which the following is a specification, reference being had to the accompanying drawing, forming part hereof, and wherein Fig. 1 is a side elevation, Fig. 2 a plan view, and Fig. 3 a rear elevation of a scrubbing machine showing my new design.

The handle, shown in dotted lines in all views, is broken away in Figs. 1 and 3 for lack of room to show it complete. The dominant feature of my design resides in the portions shown in full lines.

I claim:

The ornamental design for a scrubbing machine as shown and described.

ALBERT B. BEITMAN.
